for Lemuel W. Penell
UNITED STATES PATENT OFFICE.

CHARLES WEINBERG, OF NEW YORK, N. Y., ASSIGNOR TO C. WEINBERG & CO., OF SAME PLACE.

DESIGN FOR A GALLOON.

SPECIFICATION forming part of Design No. 19,727, dated March 25, 1890.

Application filed January 27, 1890. Serial No. 338,288. Term of patent 7 years.

To all whom it may concern:

Be it known that I, CHARLES WEINBERG, a citizen of the United States, residing at New York, in the county of New York and State 5 of New York, have invented a new Design for Galloons, of which the following is a specification.

The design of the galloon is shown in the accompanying photograph.

10 The leading feature of the design consists in the design of the central raised cords, the adjacent diagonal figures, and the wave cords near the edges of the galloon, the whole forming an ornamental and artistic article of manufacture. The longitudinal stripes *b* are 15 adjacent to the edges *a*, and have transverse

lines composing wave-formed cords. The stripes *c* are ornamented by raised cords, forming diagonal figures, as shown, and the central stripes *d* have longitudinal and transverse raised cord ornaments, composing rectangular figures, as shown. 20

I claim—

The design of the galloon, substantially as shown. 25

Signed by me this 21st day of January, 1890.

CHARLES WEINBERG.
